HERMANN STELZNER, OF LÜBECK, GERMANY, ASSIGNOR TO DRÄGERWERK HEINRICH UND BERNHARD DRÄGER, OF LÜBECK, GERMANY.

PROCESS AND APPARATUS FOR SUPPLYING AIR AND OXYGEN OR THE LIKE TO INDEPENDENT DEEP-DIVING APPARATUS.

1,180,744.

Specification of Letters Patent. Patented Apr. 25, 1916.

Application filed August 30, 1913. Serial No. 787,536.

To all whom it may concern:

Be it known that I, HERMANN STELZNER, subject of the German Emperor, residing at Lübeck, Germany, have invented certain new and useful Improvements in Processes and Apparatus for Supplying Air and Oxygen or the like to Independent Deep-Diving Apparatus, of which the following is a specification.

10 This invention relates to independent diving apparatus, that is to say, diving apparatus of the kind wherein instead of the diver being supplied with fresh atmospheric air, pumped from the outside, the air exhaled by the diver is purified by passing through a cartridge of carbonic acid whereupon after having been enriched with oxygen, it is returned in a cycle to be breathed in again by the diver. In independent 15 diving apparatus of this kind where the diving apparatuses are designed for use for small depths about 20 meters, pure oxygen is employed for effecting the circulation of the air and for replacing oxygen of the 20 expired air. In diving apparatus, however, which are designed for use at great depths, either compressed air, or a mixture of compressed air and oxygen is used, because pure oxygen is injurious to health at depths of 25 30 more than 20 meters.

Now according to the present invention, instead of using compressed air alone or oxygen alone or a mixture of both, for independent deep diving apparatus the compressed air and the oxygen are supplied separately from each other to the diving apparatus, and they are mixed together in the proper proportion only when they have arrived in the actual diving apparatus.

40 The improvement hereby achieved according to this invention, as compared with the use of compressed air alone, will be understood from the following. A man doing hard work consumes per minute one liter 45 of oxygen, or 10 liters of air since one liter of air contains about 0.2 liters of oxygen. Now if compressed air alone is supplied to a diving apparatus, a diver will require per minute 10 liters that is to say, in 200 minutes 50 he will require 2000 liters equal to two cubic meters of air at atmospheric pressure. Now in order to maintain a circulation of the air by means of the potash cartridge a maximum quantity of 4 liters of air only is re-

quired per minute. The remaining 6 liters 55 are therefore added only because the lungs consume the oxygen contained in those 6 liters. The oxygen (about 1.2 liters) contained in those 6 liters of air may therefore be supplied separately. This will produce 60 a mixture of 4 liters of air containing 0.8 liters of oxygen, 3.2 liters of nitrogen, and 1.2 liters of oxygen; that is to say, a mixture of 5.2 liters containing about 38.5 per cent. of oxygen. Thus, in this case only 5.2 65 liters per minute or 1040 liters for 200 minutes are required. A part from the saving in the work of compression since these gases can be supplied to great depth only in a compressed state, this invention has therefore the highly important advantage that the containers for the gases can be made smaller and therefore the apparatus is not so bulky. This saving in space is obviously 70 of the highest importance when diving in narrow places, for instance in wrecks and the like. Further, the weight of the entire apparatus is diminished by this invention. Also as regards the use hitherto of a mixture of compressed air and oxygen, the separate supply of compressed air and oxygen according to this invention has numerous 75 advantages. It is a comparatively difficult matter to produce from compressed air and oxygen a mixture having constantly the correct proportions of 38.5 per cent. of oxygen and the rest nitrogen, so that the mixture of compressed air and oxygen supplied to the diver will contain sometimes too much oxygen and at other times too little oxygen. 80

It is particularly difficult for workmen to fill containers with correct mixtures because the indications of the pressure gage must always be taken into consideration. It has therefore been necessary to make analytic 95 tests of the gases now and then. All this causes great difficulty in working compared with the system of keeping the two gases separate according to this invention.

One form of the invention is illustrated 100 by way of example in the accompanying drawing.

As shown *p* is a compressed air container, *s* is an oxygen container, *t* is a potash cartridge, *z* is an injector for producing the 105 circulation of the air, *r*¹ and *r*² are pressure-reducing valves. The course of the air to be breathed is indicated by arrows. The

pressure reducing valve r^2 is not absolutely necessary. A single pressure-reducing valve would suffice for the two gases because if it is assumed that there is the same equal initial pressures in the two containers, the gases will mix in almost exactly the proportion of the capacities of the two vessels, and they will leave the injector in the form of a mixture having that proportion.

10 Instead of making the proportion between the capacities of the two vessels to suit the desired mixing proportion of the two gases, the charging of the two compressed air and oxygen containers may be effected under 15 suitably different respective pressures. For instance, if the oxygen container and the compressed air vessel container have each a capacity of two liters, and if the first container is filled with oxygen under a pressure 20 of 100 atmospheres, and the other container is filled with compressed air having a pressure of 200 atmospheres, then on opening the two containers and when the pressures have become equalized, there will be a pressure 25 of 150 atmospheres in each container, and in the oxygen container, there will be 200 liters of oxygen plus 100 liters of air which latter have issued from the container that was filled with compressed air (200 atmospheres). On flowing out, the contents 30 of the two containers will mix together once more so that now a mixture will issue containing about 47.3 per cent. of oxygen and 52.7 per cent. of nitrogen. Now, if compressed air at 150 atmospheres is charged 35 into the one container and the other container is charged with oxygen at 150 atmospheres this would produce a mixture of 60 per cent. of oxygen and 40 per cent. of nitrogen and therefore, too much oxygen 40 would emerge at great depths.

Claims:

1. An independent deep diving apparatus supplied with oxygen and air or any indifferent gas, comprising a circulation conduit for the breathing air, means for absorbing the carbonic acid contained in said air inserted in said conduit, a compressed air tank, an oxygen tank, both said tanks communicating with said circulation conduit and a pressure reducing valve between the compressed air tank and the circulation conduit.

2. The herein described method of supplying oxygen and air to independent diving apparatus for greater depths, consisting in separately supplying the oxygen and the air to the diving apparatus and mixing them only when the apparatus is in operation.

3. The herein described method of supplying oxygen and air to independent diving

apparatus for greater depths, consisting in separately supplying the oxygen and the air to the diving apparatus and mixing them only when the apparatus is in operation at a ratio of substantially 20 parts of air to 6 parts of oxygen.

4. An independent deep diving apparatus supplied with oxygen and air, comprising a circulation conduit for the breathing air, means for absorbing the carbonic acid contained in said air, inserted in said conduit, a vessel for compressed air and a vessel for oxygen in communication with said circulation conduit, the volumes of said vessels being made to correspond to the ratio of the quantity of air and oxygen respectively required.

5. An independent deep diving apparatus supplied with oxygen and air, comprising a circulation conduit for the breathing air, means for absorbing the carbonic acid contained in said air, inserted in said conduit, a vessel with compressed air and a vessel with compressed oxygen, said vessels being of different sizes and in communication with said circulation conduit, the ratio of the pressure of the air and the oxygen respectively and the ratio of the size of the two vessels corresponding to the ratio of the quantity of the two gases required.

6. An independent deep diving apparatus supplied with oxygen and air, comprising a circulation conduit for the breathing air, means for absorbing the carbonic acid contained in said air, inserted in said conduit, a vessel for compressed air and a vessel for oxygen communicating with said circulation conduit, the volume of the oxygen vessel and the volume of the air vessel being made at a ratio of about 6 to 20.

7. An independent deep diving apparatus supplied with oxygen and air, comprising a circulation conduit for the breathing air, means for absorbing the carbonic acid contained in said air, inserted in said conduit, a vessel for air and a vessel for oxygen, an injector, the former vessel communicating by said injector with a point of the said circulation conduit ahead of the said absorbing means, the latter vessel communicating with a point of said circulation conduit behind said absorbing means, the volumes of said vessels corresponding to the ratio of the quantity of air and oxygen respectively required.

In testimony whereof I affix my signature in presence of two witnesses.

HERMANN STELZNER.
